US00D982797S

(12) **United States Design Patent** (10) **Patent No.:** **US D982,797 S**
Wang (45) **Date of Patent:** **** Apr. 4, 2023**

(54) **LAMP**

(71) Applicant: **Lei Wang**, Shenzhen (CN)

(72) Inventor: **Lei Wang**, Shenzhen (CN)

(**) Term: **15 Years**

(21) Appl. No.: **29/811,818**

(22) Filed: **Oct. 17, 2021**

(51) LOC (14) Cl. **26-05**

(52) U.S. Cl.

USPC **D26/60**

(58) **Field of Classification Search**

USPC D26/24, 37, 43, 60-63, 64, 65, 93, 102

CPC F21K 9/00; F21K 9/20; F21L 4/00; F21L 4/005; F21L 4/06; F21S 9/00; F21S 9/02; F21V 21/042; F21V 21/08; F21V 21/088
